UNITED STATES PATENT OFFICE.

EDWARD C. LEIMAN, OF NUTLEY, NEW JERSEY, ASSIGNOR TO LEIMAN BROS., OF NEW YORK, N. Y., A CORPORATION COMPOSED OF WILLIAM H. LEIMAN, GEORGE W. LEIMAN, GUSTAVE A. LEIMAN, EDWARD C. LEIMAN, AND JOHN LEIMAN.

PUMP AND MOTOR MOUNTING.

Application filed February 24, 1923. Serial No. 620,885.

To all whom it may concern:

Be it known that I, EDWARD C. LEIMAN, a citizen of the United States, and resident of Nutley, in the county of Essex and State of New Jersey, have invented a new and useful Improvement in Pump and Motor Mountings, of which the following is a specification.

This invention relates to a pump and motor mounting and has for its object to provide a base for the motor and a support for the pump, said base and support being arranged in different horizontal planes.

Another object is to provide a unitary structure having a base for the motor and a support for the pump, said support being formed with an oil reservoir for supplying oil for lubricating purposes.

Another object is to provide a unitary structure including a reservoir connected with the pump whereby air pressure is applied to the reservoir for feeding oil under pressure.

Another object is to provide an audible indicator for the reservoir for signaling the level of the oil in the reservoir, which indicator is arranged to be operated by the pressure of air in the reservoir.

Another object is to provide certain improvements in the form, construction and arrangement of the parts whereby the above named and other objects may be effectively attained.

A practical embodiment of my invention is represented in the accompanying drawings, in which—

Fig. 1 represents a vertical central section taken through the mounting, portions of the pump being broken away to show other parts more clearly.

Fig. 2 represents a vertical section taken in the plane of the line II—II of Fig. 1, and

Fig. 3 represents a detail vertical section, on an enlarged scale of the audible signal for the level of the oil in the reservoir.

The mounting comprises a unitary structure having a base denoted by 1, upon which is fixed a motor 2, which base is provided with a peripheral rim 3 and depending sides 4.

An oil reservoir is formed integral with the base 1 and sides 4, which reservoir com-

prises a bottom 5 and side walls 6, the upper portion of the side walls extending above the base 1 so as to increase the capacity of the reservoir.

A cover 7 is removably secured to the side walls 6 by means of screws 8. The base 1 and cover 7 are arranged in different horizontal planes so that the pumps 9 and 10 will be supported in position on the cover 7 with their shaft 11 in alignment with the shaft 12 of the motor 2. The pump shaft 11 and motor shaft 12 are connected by a coupling 13.

Lugs 14 extend laterally at intervals from the sides 4 and walls 6 and serve as a means by which the structure may be secured against displacement.

To provide a pressure of air within the reservoir, one side of the pump 9 is connected to the cover of the reservoir by means of a pipe 15, the end of which is arranged to extend a slight distance below the cover 7 in position to receive a strainer 16. An outlet pipe 17 is secured to the cover 7 and also provided with a strainer 18. Thus it will be seen that by reason of the air passing from the pump through the pipe 15 into the reservoir and thence through the outlet pipe 17 to a storage tank (not shown) or to be used as desired, a constant air pressure will be maintained in the reservoir. By means of this pressure of air in the reservoir, I am enabled to force oil upwardly through pipe connections 19, in the present instance two are shown, which connections lead to bearings 20 of the shaft 11 of the pump 9. Each connection 19 has a screen 21 at its lower end to prevent foreign matter from being passed therethrough. While I have shown pipe connections 19 for supplying oil to the bearings 20, of the pump shaft 11, I wish it understood that similar connections may be inserted in the reservoir and arranged to supply oil to other parts of the pump, the motor or other machines (not shown).

In order to announce that a predetermined low level of oil in the reservoir has been reached, I provide a signal which will automatically operate to sound an alarm by the pressure of air in the reservoir, which signal is constructed and operated as follows:

A nipple 22 having a screw threaded engagement with the cover 7 is arranged to receive a tubular member 23, the upper end of which is provided with a valve seat 24 arranged to coact with the needle valve 25 fixed to the upper end of a hollow stem 26 carried by a float 27, of cork or other similar material. The lower end of the tubular member 23 has a bushing 28 which forms a journal in which the stem 26 slides. A signal or audible alarm in the form of a whistle 29, of well known and approved construction, is secured to the upper portion of the nipple 22 and arranged to be operated by allowing the pressure of air in the reservoir to enter the tubular member 23 through a hole 30, so that as the valve 25 moves away from its seat 24 the air will escape from the reservoir through the hole 30 in the member 23 and thence between the valve and its seat into and through the whistle 29, thereby sounding the alarm and audibly signaling the fact that the low level of the oil in the reservoir has been reached. Any amount of oil in the reservoir above the predetermined low level will cause the float to hold the needle valve on its seat until a certain level has been reached and as the oil is withdrawn through the connections, the level of the oil will fall until the float 27, through its stem 26, will draw the needle valve from its seat and open communication with the air in the reservoir through the hole 30 in the tubular member 23.

As a convenient means for replenishing the oil in the reservoir, I provide an opening 31, (shown in dotted outline in Fig. 1) located at the junction of the base and one of the side walls of the reservoir, which opening is screw threaded and provided with a plug 32. A pet cock 33 is disposed near the bottom of the reservoir for removing the oil for purposes of cleaning the reservoir or withdrawing any surplus amount of oil.

It is evident that various changes may be resorted to in the form, construction and arrangement of the several parts without departing from the spirit and scope of my invention; hence, I do not intend to be limited to the specific details herein shown and described, except as they may be included in the claims.

What I claim is:

1. A pump and motor mounting having a base for the motor, an oil reservoir ad-

jacent said base and provided with walls extending upwardly above the base, a cover removably secured to said walls, a pump mounted on the cover and provided with means connected with the reservoir through the cover for applying pressure thereto, and an oil supplying means connecting the reservoir and pump through the cover.

2. A pump and motor mounting having a base for the motor, an oil reservoir adjacent said base and provided with walls extending upwardly above the base, a cover removably secured to said walls, a pump mounted on the cover and provided with means connected with the reservoir through the cover for applying pressure thereto, an oil supplying means connecting the reservoir and pump through the cover, and an outlet in the cover for the compressed air.

3. A pump and motor mounting having a base for the motor, an oil reservoir adjacent said base and provided with walls extending upwardly above the base, a cover removably secured to said walls, a pump mounted on the cover and provided with means connected with the reservoir through the cover for applying pressure thereto, an oil supplying means connecting the reservoir and pump through the cover, an outlet in the cover for the compressed air, and an audible indicator mounted in the cover and operated by the air pressure in the reservoir for sounding an alarm at a predetermined level of the oil in the reservoir.

4. A pump and motor mounting having a base for the motor, an oil reservoir adjacent said base and provided with walls extending upwardly above the base, a cover removably secured to said walls, a pump mounted on the cover and provided with means connected with the reservoir through the cover for applying pressure thereto, an oil supplying means connecting the reservoir and pump through the cover, an outlet in the cover for the compressed air, and an indicator for the level of the oil in the reservoir, said indicator comprising a sound producing device mounted in the cover and a float arranged to coact with said sound producing device to control the pressure of air to the sound producing device.

In testimony that I claim the foregoing as my invention, I have signed my name this 21st day of February, 1923.

EDWARD C. LEIMAN.
